UNITED STATES PATENT OFFICE.

THEODORE R. BRIEN, OF HOOSICK FALLS, NEW YORK, ASSIGNOR OF ONE-HALF TO GEORGE O. WALRAD AND LOUIE J. BRIEN, OF SAME PLACE.

NIPPLE CONNECTION.

SPECIFICATION forming part of Letters Patent No. 530,679, dated December 11, 1894.

Application filed March 20, 1894. Serial No. 504,400. (No model.)

To all whom it may concern:

Be it known that I, THEODORE R. BRIEN, a citizen of the United States, residing at Hoosick Falls, county of Rensselaer, and State of New York, have invented certain new and useful Improvements in Nipple Connections, of which the following is a specification.

My invention relates to such improvements and consists of the novel construction and combination of parts hereinafter described and subsequently claimed.

Reference may be had to the accompanying drawings, and the letters of reference marked thereon, which form a part of this specification.

Similar letters refer to similar parts in the several figures therein.

Figure 1 of the drawings is a central longitudinal section of a nipple and pipe in connecting position, showing in side elevation the hinge-coupling in engagement with the nipple and pipe. Fig. 2 is a view in side elevation of the connected parts. Fig. 3 is a top plan view of the hinge-coupling detached and partially open or distended. Fig. 4 is a view in side elevation of a detached nipple having an integral annular flange.

A—represents the nipple which is commonly an iron casting made integral with and projecting from some larger body, as for example, the bottom of a kitchen sink.

B—represents a metal pipe, commonly a lead pipe which is especially adapted for use as a waste pipe for sinks.

C—, and C'—represent the two sections of a hinge-coupling by which the lead pipe is clamped upon the iron nipple in a manner to make a tight joint between the nipple and pipe.

I have shown the nipple provided externally with an annular flange A²—secured to the nipple by screws, S—, as shown in Fig. 1.

The upper side of the flange, or that side adjacent to the upper end or base of the nipple, is inclined inwardly and downwardly, while the lower or outer end of the nipple is oppositely inclined inwardly and downwardly, thus giving the lower or attaching end of the nipple a conical form.

When desired, the flange may be cast integral with the nipple, as shown in Fig. 4.

The end of the pipe to be connected to the nipple is expanded, or made flaring to approximately fit the conical end of the nipple inserted therein.

The coupling comprises two semicircular sections C— and C'—hinged together as by the pivot C²—inserted in the radially-projecting lugs C³— and C⁴—on the respective sections, so that when the hinged sections are 60 swung together or closed, they together form a ring. Each section is also provided with a perforated lug C⁵—diametrically opposite the hinge-lugs, adapted to receive a screw-threaded bolt C⁶—. Each section is provided 65 with oppositely inclined inner surfaces C⁷— and C⁸—, the surface C⁷— being adapted to engage the correspondingly inclined upper surface of the nipple-flange, and the surface C⁸— to engage the nipple-inclosing portion of 70 the pipe, as shown in Fig. 1.

To connect the nipple and pipe, it is only necessary to insert the conical end of the nipple in the flaring end of the pipe, place the coupling around such ends and the nipple-flange and tightly clamp the coupling thereon in any known manner, as by the bolt C⁶— and thumb-nut C⁹— fitting such bolt.

It is apparent from an inspection of Fig. 1, that when the coupling-sections are forced together after engaging the lower part of the inclined surface of the nipple-flange, they are also forced upward toward the base of the nipple by such inclined surface, thereby forcing, by means of the inclines C⁸— the flaring portion of the pipe up onto the thicker or larger portions of the nipple until the pipe is tightly clamped between the coupling and the nipple.

The inclines above described enable me to tightly connect a rigid unyielding pipe having a flaring mouth, upon a rigid nipple, or a relatively yielding pipe like lead pipe having a straight cylindrical mouth, because the yielding material permits the pipe to readily conform to the shape of the relatively rigid and unyielding nipple.

What I claim as new, and desire to secure by Letters Patent, is—

1. The combination with a nipple having an exteriorly projecting annular flange, and made of relatively rigid material, of a nipple-inclosing pipe made of a relatively yielding

material, a hinge-coupling inclosing the nipple-flange and the nipple-inclosing portion of the pipe, and means for clamping the coupling upon such flange and pipe, substantially as described.

2. The combination with a conical flanged nipple having the side of the flange adjacent to the base of the nipple oppositely inclined to the inclined wall of the nipple, and a pipe having a nipple-inclosing flaring mouth, of a hinge-coupling provided with oppositely inclined inner surfaces adapted to engage re-

spectively the inclined surface of the nipple-flange and the nipple-inclosing portion of the pipe, and means for clamping the coupling upon such flange and pipe, substantially as described.

In testimony whereof I have hereunto set my hand this 13th day of March, 1894.

THEODORE R. BRIEN.
